[57] CLAIM

The ornamental design for an element for a toy building set, as shown and described.

DESCRIPTION

FIG. 1 is a top perspective view of an element for a toy building set showing my new design;

FIG. 2 is a front elevational view thereof;

FIG. 3 is a side elevational view thereof, the side opposite being a mirror image;

FIG. 4 is a rear side elevational view thereof;

FIG. 5 is a top plan view thereof; and,

FIG. 6 is a bottom plan view thereof.

FIG. 1

FIG. 2

FIG. 3

FIG. 4

FIG.5

FIG.6
